UNITED STATES PATENT OFFICE.

JOHN RICHARD HUGHES, OF CHAMA, TERRITORY OF NEW MEXICO,
ASSIGNOR TO J. R. HUGHES INVENTION CO., OF CHAMA, TERRI-
TORY OF NEW MEXICO.

WHIFFLETREE-HOOK.

No. 825,216.

Specification of Letters Patent.

Patented July 3, 1906.

Application filed July 26, 1905. Serial No. 271,313.

To all whom it may concern:

Be it known that I, JOHN RICHARD HUGHES, a citizen of the United States, and a resident of Chama, in the county of Rio Arriba and 5 Territory of New Mexico, have invented a new and Improved Appliance for Vehicles, of which the following is a full, clear, and exact description.

This invention relates to appliances for vehicles; and it consists, substantially, in the details of construction and combinations of parts hereinafter more particularly described, and pointed out in the claims.

This invention has reference more especially to draft appliances for the ends of either swingletrees or doubletrees (or as may also be said of whiffletrees) of vehicles for the attachment thereto of tugs of harness-traces.

One of the principal objects of the invention is to provide an appliance of this kind which is exceedingly simple in its embodiment and comparatively inexpensive to manufacture, besides being strong and durable, easily and readily replaced when worn or broken, both effective and reliable in use, and possessing capacity for long and repeated service.

The above and additional objects are attained by means substantially such as are illustrated in the accompanying drawings, in which—

Figure 1 is a side view of a device embodying my improvements, the swingletree or other member on which the device is applied being shown in section. Fig. 2 is a top plan view. Fig. 3 is a transverse sectional view on the line 3 3 of Fig. 1, and Fig. 4 is a view in perspective of one of the duplicate hooks employed.

Before proceeding with a more detailed description it may be stated that in the form of my improvements herein shown I employ a special appliance for the purpose mentioned 45 comprising duplicate reversely-disposed hooks of special embodiment for engagement therewith of a specially-constructed double cockeye having a tug for attachment to or connection with the end of an ordinary harness-trace. The embodiment is such that when the double cockeye on the trace-tug is applied to or connected with the said hooks it is practically impossible for the same to be-

come accidentally disconnected therefrom, irrespective of the directions or angles assumed by the tug under ordinary conditions of operation.

While I have here represented my improvements in a certain preferred embodiment, it will be understood that I am not limited thereto in precise detail, since immaterial changes therein may be made coming within the scope of my invention.

Reference being had to the drawings by the designating characters thereon, 1 represents a portion of either a swingletree or a doubletree of an ordinary draft device for vehicles, closely fitted to which at the end or other suitable part thereof is a collar or band 2, formed with duplicate eyes 3, preferably extending upwardly therefrom and which may occupy any relative position with reference to same as may be desired in practice. Fitting loosely within each of the said eyes 3 and freely encircling the said collar or band 2 as thus applied to the swingletree or doubletree 1 is a ring-shaped shank 4, which at 5 merges into a hook 6, the bill 7 of which is returned in substantially the same plane and has the end thereof outturned at 8, (see Figs. 1 and 2,) it being observed that the two hooks are opposite to each other and reversely disposed one above the other, as shown in Fig. 1. The free extremities of the hooks extend as close to the said ring-shaped shanks thereof as is practicable, and in making connection of an ordinary harness-trace 9 with the swingletree or doubletree 1 each of the eyes 10 of the double cockeye 11, to which the trace is movably connected at 12, is slipped over the said bill 7 of one of the said duplicate hooks, and it will be seen that a most effective and reliable fastening or attachment for the trace to the swingletree or doubletree is thus derived.

From the construction above described it will be seen that as the draft strain may be imposed upon the trace 9 the said ring-shaped shanks of the duplicate hooks will be swung or moved in such manner as that the rearward portions 13 thereof will be caused to bear against the corresponding surface portions of the collar or band 2, and thus will the draft strain be assisted to be borne as well as partly neutralized, and thus obviating in a very great measure any disconnection or breakage between the parts of the

structure set forth. As herein represented in the particular application of my improvements shown, the hooks are disposed in horizontal planes; but it is apparent that in other uses thereof it may be desired to use them either in vertical or other planes, all of which will be considered to be comprehended by my invention. In some instances a single one only of my improved duplicate-hook structure may be employed in various uses, as will be understood.

Having thus described my invention, I claim as new and desire to secure by Letters Patent—

- 15 1. An appliance for swingletrees or double-trees of vehicles, comprising duplicate reversely-disposed hooks, and a tug having a double cockeye for engagement with the bills of the hooks.
- 20 2. A device of the character described having a band for application to a support therefor, having double eyes thereon, and duplicate hooks having ring-shaped shanks fitting loosely within the eyes and encircling said band.
- 25 3. A device of the character described having a band for application to a support therefor, having double eyes thereon, and dupli-

cate hooks having ring-shaped shanks fitting loosely within the eyes and encircling said band, the hooks being reversely disposed to each other.

4. A device of the character described having a band for application to a support therefor, having double eyes thereon, duplicate hooks having ring-shaped shanks fitting loosely within the eyes and encircling said band, the hooks being reversely disposed to each other, and a double cockeye for engagement with the hooks.

5. An appliance for swingletrees and double-trees of vehicles, comprising a band to be fitted to a support and having double eyes, and duplicate hooks having ring-shaped shanks for encircling the band.

6. An appliance for swingletrees and double-trees of vehicles, comprising double hooks, and a tug having a double cockeye for engagement by the bills of the hooks.

In testimony whereof I have signed my name to this specification in the presence of two subscribing witnesses.

JOHN RICHARD HUGHES.
